UNITED STATES PATENT OFFICE.

JAMES E. LINDSAY, OF SELMA, LOUISIANA.

HOSE AND GARMENT SUPPORTER.

1,343,514.

Specification of Letters Patent. Patented June 15, 1920.

Application filed June 3, 1919, Serial No. 301,379. Renewed March 4, 1920. Serial No. 363,285.

To all whom it may concern:

Be it known that I, JAMES E. LINDSAY, a citizen of the United States, residing at Selma, in the county of Grant and State 5 of Louisiana, have invented certain new and useful Improvements in Hose and Garment Supporters, of which the following is a specification.

This invention relates to hose and garment supporters and more particularly to an improved device for gripping the hose or garment to support the same in a manner that will prevent injury being done to the garment.

15 One of the objects of the invention is to provide a device of this character which may be quickly and readily detached from the supporting strap but which will be so constructed as to prevent accidental or 20 casual detachment.

A further object of the invention is to provide a supporting device of this character which will include all of the desired features which go to make an improved 25 article of this character but which will be constructed so that the device will lie flat and afford comfort to the wearer and will not cause a bulging or distorting of the outer garments.

30 A further object of the invention is to provide a device of this character which will include elongated jaws suitably covered with removable covering which is mounted so that it may be renewed when desired.

35 The above and additional objects are accomplished by such means as are illustrated in the preferred embodiment and in the accompanying drawings, wherein like characters denote like or corresponding parts 40 throughout the several views, in which:—

Figure 1 is an elevation of the device constructed in accordance with my invention.

Fig. 2 is a section taken on the line 2—2 of Fig. 1.

45 Fig. 3 is a section taken on the line 3—3 of Fig. 1, the jaws being shown in open position.

50 Fig. 4 is an enlarged detail fragmentary elevation of a portion of the attaching member, parts being shown in section to more clearly disclose the structure.

Fig. 5 is a plan of the blank form which provides the covering for the curved jaws.

55 Fig. 6 is a detail view of a portion of the invention.

Referring particularly to the drawings

wherein is illustrated the preferred form of my invention, the supporting strap 1 is attached to a supporting band or to a portion of the garment in any preferred manner and is equipped with a loop 2.

An attaching loop or bar 3 is connected with the loop 2 and this member consists of the substantially U-shaped tubular element 4, the open ends of which are adapted 65 to receive the locking element 5 which is also U-shaped and cooperates with the U-shaped member 4 to form the attaching bar. One of the edges of the member 5 is provided with a recess 6 to the bottom of which 70 is attached a flat spring 7 carrying a stud 8. The member 5 is inserted in the open ends of the member 4, this stud 8 is adapted to register with an opening 9 in one of the legs of the U-shaped member 4 to prevent 75 displacement or detaching of the members until such time as the member 8 is pushed inwardly by the user. This device it will be noted provides parallel bars, one of which engages the loop 2 and the other is 80 adapted to receive the jaw supporting arms 10 and 11. The arms 10 and 11 are formed of a single strip of material bent intermediate its ends to form the loop 12 which passes over the lowermost of the parallel 85 arms included in the supporting member 3. The latter is provided with spaced apart lugs or projections 13 shown to advantage in Fig. 1, and between these projections the loop 12 is mounted and it will be obvious 90 that the relative movement of the supporting arms 10 and 11 on the supporting member 3 will be prevented by this construction.

The arms 10 and 11 are provided with a longitudinally slidable ferrule 14 which is 95 adapted to close and open the lower ends of the arms as the ferrule is longitudinally moved thereon. Each of the arms is provided with a lug 15 which may engage above the ferrule as shown in Fig. 1 when the ferrule 100 is moved to its lowermost position thereby maintaining the ferrule in position against upward sliding movement.

Attached to each of the arms 10 and 11 is a curved jaw member 16 which is longitudinally curved as shown in Fig. 2 to conform to the curvature of the leg of the wearer. Each jaw member 16 is covered with a removable cover 17 which is shown detached in Fig. 5. The material is preferably sheet rubber or similar resilient material and consists of the elongated strip

17 having the flaps 18 attached to the opposite marginal edges and spaced apart to provide the gaps 19 whereby the arms 10 and 11 may be secured in position. One 5 face of the central strip portion 17 is provided with corrugations 20 and these corrugations are adapted to register when the jaws are closed to more effectively maintain a garment in firmly fixed position between the jaws. At each end of the strip member 17 is a pocket 21 shown in Figs. 5 and 6 and each pocket is adapted to receive one end of the corresponding jaw 16 and since the jaws have a certain amount of resiliency it will be obvious that they may be readily sprung closed together into position in the pocket, after which the flaps 18 are bent over the back portions of the jaws and glued, pasted, or otherwise secured together so that the jaws are entirely embraced by the covering material. By virtue of this construction, the renewing of the covering for the jaws is easily accomplished.

The foregoing description and accompanying drawings have reference to what might be considered to be the approved or preferred form of my invention. I desire it to be understood that I may make such changes in the construction, combination and arrangement of parts, materials, dimensions, et cetera, as may prove expedient and fall within the scope of the appended claims.

Having thus fully described my invention what I claim as new and desire to secure by Letters Patent is:—

1. A garment supporter comprising supporting arms having elongated arcuate jaws secured to their terminals, each jaw being

provided with a covering, the said covering having pockets in its ends to receive the ends of the said jaws, the approximate surfaces of the covering being corrugated, and flaps formed on the covering and adapted to be glued together to maintain the covering in position on the said jaws.

2. A garment supporter comprising supporting arms arcuate jaws attached to the ends of the arm, each jaw being provided with a covering comprising a strip of rubber material having a corrugated surface and provided with flaps adapted to overlap the back of the jaws and the said covering having end pockets to receive the ends of the jaws, the said flaps being adapted to be fastened together at the back of each jaw to maintain the said covering in position on the jaws and to facilitate renewal of the said covering when worn.

3. A garment supporter comprising a supporting loop, jaw carrying arms also having a loop, an attaching member comprising a U-shaped element having its parallel arms received in the said loops, the said parallel arms having open ends, a removable U-shaped member adapted for insertion in the open ends of the said parallel arms, and locking means carried by one of the arms and engageable with one of the open ends of the said element to close the space between the open ends of the said parallel arms.

In testimony whereof I affix my signature in presence of two witnesses.

JAMES E. LINDSAY.
